MATRIX DISTRIBUTOR CONTROL FOR LINE
COMPOSING MACHINESMaurus T. Goetz, Chicago, Ill., assignor, by mesne
assignments, to Teletypesetter Corporation, a
corporation of Delaware

Application February 16, 1935, Serial No. 6,824

3 Claims. (Cl. 199—43)

The present invention relates to linecasting and composing machines which utilize circulating matrices and more particularly to linecasting and composing machines operated from an automatically operated controlling unit.

In conventional types of line composing machines served by a plurality of sets of circulating matrices there is employed a line composing mechanism for releasing the matrices from a storage magazine, and an elevator for moving assembled lines of matrices from a position at which they are arranged in the sequence of line composition to a level from which they may be delivered to the casting mechanism. A line delivery slide thereafter moves the assembled matrices to the casting mechanism and an elevator lifts the matrices after they have returned from the casting mechanism to an altitude from which they may be gravitated to the channels of the storage magazine. The distribution of the various matrices and their separation into the respective channels of the magazine from which they originate is executed by a coded distributor bar and a set of screw threaded conveyor shafts ordinarily in continuous rotation but capable of being instantaneously arrested upon a very slight interference with their movement, as by a blocking or jamming, due to a misalignment of the matrices.

According to a feature of the present invention, automatic line composition is arrested in the event that the matrix distributor shafts are disabled, thereby bringing the entire machine to rest and preventing the depletion of any of the classes of character matrices which might otherwise follow because of the corresponding exhaustion of those characters during the composition of subsequent lines of matrices and the disability of the matrix distributing apparatus.

It is an object of the present invention to provide a simple and reliable device operative in response to an improper operation of the distributor shaft of a linecasting machine for interrupting the operation of the automatic control unit.

In attaining the foregoing object, the present invention contemplates the provision of a control switch presented endwise of one of the distributor conveyor shafts and a control switch operating mechanism associated with one of the distributor shafts and responsive centrifugally to its rotation. The automatic operating mechanism illustrated in connection with a preferred embodiment of the present invention corresponds to the structure more fully disclosed and de-

scribed in copending application Serial No. 600,606, filed March 23, 1932, a portion of which is illustrated in the accompanying drawings. In this type of apparatus there is employed a record reader operating shaft which carries several actuating elements that function to sense and advance a perforated control form. An operating magnet or solenoid, actuated in response to the closure of a circuit controlled by a centrifugally operated mechanism related to the distributor shafts and operated when they become impaired, renders the record reader ineffective by disengaging the clutch through which power is furnished from the source of power to advance the control form.

For a comprehensive understanding of the present invention, reference may be had to the accompanying drawings and to the following detailed specification in each of which similar reference characters have been assigned to corresponding parts throughout. In the drawings:

Fig. 1 is a perspective view of a portion of the operating unit featuring the record reader mechanism and its operating shaft;

Fig. 2 is a rear elevation of one end of a conventional type of linecasting and composing machine, featuring a duplex distributor apparatus including one embodiment of the present invention applied thereto;

Fig. 3 is a detailed elevational view partially in section taken approximately on line 3—3 of Fig. 2;

Fig. 4 is a detailed plan view taken approximately on line 4—4 of Fig. 3 illustrating partially in section the centrifugal switch mechanism;

Fig. 5 is a transverse sectional view through a portion of the operating mechanism illustrated in Fig. 1, and

Fig. 6 is a detailed elevational view of the centrifugal switch mechanism illustrated in Fig. 4.

The functions of a linecasting and composing machine may be generally summarized as including matrix composition, line casting, and matrix distribution. In the adaptation of automatic control mechanism to the supervision of the aforementioned functions, a unitary structure has been devised for coordinating the various functions and for intercontrolling their performance so that in the event of certain possible irregularities of operation, predetermined emergency responses will follow.

Referring now more particularly to the drawings, a fragment of perforated tape is indicated by the reference character 11. The transverse

perforations in this record are successively sensed by a set of feeler levers 12 cyclically withdrawn by a cam 13 and permitted to return by individual return springs (not shown) alternately. 5 The cam 13 is secured to a continuously rotatable shaft 14 to be generally referred to herein-after as the record reader operating shaft. Another cam 15, also carried by shaft 14, cyclically stimulates a linkage for intermittently advancing the tape 11. The tape sensing and tape advancing functions follow in alternative succession and coincide with each revolution of the shaft 14.

Power for rotating the record reader operating shaft 14 is obtained from a continuously rotated driving shaft, not shown in the particular illustration, but described in the copending application referred to above. The driving connection is obtained from the aforesaid shaft 14 through gear 16 and is communicated through the elements of a tooth clutch 17, the driven portion of which may be withdrawn when, upon the intervention of a blocking lever 18, a projection 19 carried by said driven portion of clutch 17 is engaged by an inclined surface of a co-operating projection 65 carried upon the adjacent side of the lever 18. The control lever 18 is pivotally carried at 21 and is connected at its opposite end 22 to a link 23 which, as described in the application referred to, actuates the lever 18 under the control of a certain signal allotted to the selective conditioning of an assembler elevator selector bar 24, which upon being selectively actuated rocks a three-armed lever 26 in a counterclockwise direction as viewed in Fig. 1. The detailed description of the aforesaid copending application sets forth how, among other results, in response to the selection of the bar 24, lever 18 is rocked clockwise, causing its portion 65 to be presented in the path of revolving lug 19.

In connection with the present invention, the same lever 18 is brought under the selective control of an additional supervisory element by having at its end 22, articulated through a link 25, one end of an armature lever 26 which is pivoted at 27 and whose opposite end may be selectively attracted by an operating magnet 28. Under the selective control condition about to be described, when the magnet 28 is energized, the armature 26 is rotated counterclockwise, pulling the lever 18 through the link 25 in a clockwise direction and presenting the opposite end of lever 18 into the path of projection 19 for thereby disengaging the elements of clutch 17. 55 To prevent the assembler elevator from being falsely initiated at this time, link 23 is provided with a slot connection 30 at its junction with the three-armed lever 26 so that the motion of link 23 is not communicated backward there-through.

As set forth above, the instance of the particular supervisory control is to be governed by an interruption in operation of the distributor mechanism. Accordingly, reference will now be had to Figs. 2-4 wherein there are illustrated the elements of a matrix distributor apparatus. In the particular embodiment, a commercial type of duplex distributor is illustrated which is designed to accommodate a plurality of storage magazines. However, as will be noted in the course of the following description, the principles of the present invention are equally applicable to a single distributor mechanism. Each 75 set of distributor shafts comprises three longi-

tudinal conveyor spirals indicated 31, 32, and 33. The shafts which form the spirals 31 and 33 are driven from a control shaft or shaft extension 34 by means of a set of end pinions generally indicated by the reference character 35, 5 while the shaft 32 is driven through gear 36 by a driving pinion cooperating with it and carried by the shaft of screw 31.

In connection with the particular illustration, the primary or lower set of distributor shafts are 10 driven through a pulley wheel 37 and belt 38 from the so-called intermediate shaft of the principal machine. The driving connection is communicated through a clutch generally indicated 39 designed to disconnect instantly upon the 15 slightest impairment encountered by the primary distributor shaft 41.

The primary shaft 41 through belt chain driving connection 42 rotates the secondary distributor shaft 34, which in turn communicates 20 its power to the secondary or upper set of distributor spirals 32 and 33. When an interruption of movement causes shaft 41 to become arrested, shaft 34 is simultaneously arrested. This is equally true whether the impairment which 25 trips clutch 39 arises in connection with the primary distributor system or in the secondary distributor system.

As best noted in Fig. 3, the conveyor shafts 31 and 33 are of symmetrically opposite helices to 30 that of shaft 32 so that as the set of shafts 31-33 are driven concurrently the thread grooves within their respective threads are constantly in transverse alignment, and as the spirals are rotated, the alignment is apparently advanced longitudinally with respect to a distributor bar 43 upon which the matrices 44 are suspended. A coded system of notches is arranged having various combinations of toothed clearances in transverse alignment with the channels 45 of their magazines 46. The matrices 44 may in this manner proceed longitudinally until the particular teeth thereof coincide with the clearance portions provided in the distributor bar 43, at which instant a particular matrix is precipitated into its associated channel 45.

The mechanism thus far described is well known in the art of line composing machine construction as adapted to manual control operation. Where, however, line composing mechanisms are 50 supervised by automatic control operating devices, conditions of operation may arise giving need to additional safeguard in the supervisory control affecting the aforescribed matrix distributor systems. Typical among such conditions is one which might ordinarily occur while the automatic operating unit is in continuous actuation, taxing the capacity of the casting mechanism to its limit and giving rise to a condition where one line of composed matrices is in 60 an advanced state of completion, a second line is suspended at the delivery slide level, a third in the casting chamber, and a fourth in an early stage of distribution. Thus four lines of matrices may be employed in various stages of the system 65 as a result of which certain alphabetical characters, because of their natural or special frequency of occurrence, constitute so much of the composed matter in the aforementioned four lines of composition as to deplete nearly all of the 70 available supply of the particular channel.

If under such conditions of operation the distributor shafts are arrested due to a jamming of the matrices or due to any other of several probable conditions, there may result the total de- 75

pletion of those certain characters whose supply is ordinarily low. If, when this occurs, the record reader operating unit is permitted to continue, subsequently composed lines of matrices will be assembled with the depleted matrices omitted. This disorder would not only necessitate having to readjust the machine manually at a great loss of time to determine the number of lines to be recomposed, but may also, because of the composition of too short lines, result in the jeopardous front or rear "squirts" in the vicinity of the casting chamber.

To prevent the above possibility, the present invention provides a gear 47 carried by one or the other of the distributor shaft extensions 34 or 41 (in the instant case, shaft 34). This gear, through its associated driven pinion 48, imparts a rotary motion to a stub shaft 49 which is journaled in a block 51. One end of the shaft 49 is enlarged as at 52 and thereat securely carries a housing 53 fastened by transverse screws 54. Within the housing 53 there are provided a pair of symmetrical weight elements 55 pivoted at 56, each having integrally formed with it an inwardly presented lip 57. A trigger shaft 58 in axial alignment with the stub shaft 49 has integrally formed with it a flange 59 which engages the lips 57 of the centrifugal weights 55. A slight longitudinal freedom is permitted shaft 58, but by reason of the pressure of a concentric coil spring 61, shaft 58 is urged rightwardly, as viewed in Fig. 4, causing flange 59 through the lips 57 to draw the centrifugal weights inwardly toward the shaft 58.

During the time in which the distributor shafts 31-33 are in rotation and the shaft extensions 34 or 41 through gear 47 impart the rotation to stub shaft 49, the weights 55 are centrifugally divaricated in opposition to the tendency of spring 61, causing the opposite end of shaft 58, see also Fig. 5, to be withdrawn from engagement with the contactor 62 of contact pair 63. This permits the contact pair 63 to separate, opening the circuit which originates at positive current source 64, and continues through contacts 63, conductor 64, the winding of magnet 28 to ground. Since this is the normal condition existent during the time in which the principal machine is in operation and while the distributor conveyor shafts are functioning, it may be termed the normal supervisory condition for when the principal machine is dormant, the switch control mechanism effects its disabling position but not then in a supervisory capacity.

The instant that the rotary movement is arrested and shaft 49 is stopped, the centrifugal force ceases and spring 61 is permitted to exert its influence to move shaft 58 longitudinally and close the contact pair 63. As a result of the energization of magnet 28, armature 26 is attracted, moving in a counterclockwise direction about pivot 27. Through link 25, lever 18 is moved in a clockwise direction about its pivot 21 until the projection 65 is presented into the path of the revolving projection 19 carried by the record reader actuating clutch 17, thereupon the record reader operating shaft 14 is arrested, holding in abeyance the several elements of the record reader sensing and advancing apparatus.

When the distributor shafts 31-33 are arrested due to a jamming of the matrices or due to any other of several probable conditions, clutch 39 becomes disengaged, and as a result thereof shaft 49 ceases to rotate and contacts 63 are closed, causing the energization of electromagnet 28 and

the resulting operation previously described. The removal of the matrices which became jammed or the other cause which effected the disengagement of clutch 39 and the closure of contact 63, resulting in arresting the performance of the record reader, conditions the apparatus for further operation. Further operation is achieved by rotating the knurled member secured to the free end of shaft 41, Fig. 2. Such operation of shaft 41 causes the engagement of the driven member of clutch 39 with the driving member thereof, and thus causes the rotation of the distributor shafts 31-33. The rotation of the distributor shafts of course causes the rotation of shaft 49 and due to the centrifugal action of weights 55 contacts 63 will be opened, electromagnet 28 will be deenergized, and the record reader will be started again due to the removal of projection 65 from the path of the projection 49 to allow operating shaft 14 of the record reader to be rotated through clutch 17.

Discontinuing operating power from the principal machine causes the distributor shafts 31-33 to assume their rest positions with clutch 39 engaged. Under such conditions, contacts 63 will be closed and electromagnet 28 will be energized, provided the operating power for electromagnet 28 is not removed simultaneously with the removal of operating power from the principal machine, which of course would be a desirable feature of operation. When power is again applied to the principal machine, distributor shafts 31-33 will rotate, as will shaft 49. The rotation of the latter shaft causes the weights 55 of the centrifugal mechanism to assume a position where contacts 63 will be opened, electromagnet 28 will be deenergized, and the operating shaft 14 of the record reader will be released for rotation.

While the present invention has been explained and described with reference to a particular embodiment, it will be understood that numerous modifications and variations may be made without departing from the spirit or scope thereof. Accordingly, it is not intended to be limited by the detailed illustrations in the accompanying drawings nor by the language of the foregoing description, except as indicated in the hereunto appended claims.

The invention claimed is:

1. In a line composing machine for selectively assembling and distributing a plurality of classes of circulating matrices, an automatic control unit responsive to signals for selectively releasing for assembly matrices during line composition, a rotatable distributor for moving said matrices during distributive separation, a pair of centrifugally weighted arms rotatable during the movement of said distributor, a spring for urging said arms in opposition to their centrifugal tendency imparted by said distributor, a contact controlling member movable by said spring in one direction and by said weighted arms during their centrifugal tendency in an opposite direction, and means responsive to said contact controlling member for arresting the performance of said control unit.

2. In a linecasting and composing machine, a storage magazine having a plurality of channels each adapted to receive a class of slug casting matrices, a plurality of release elements each associated with one of said channels for releasing matrices in accordance with signals stored in a tape, a mechanism for sensing the signals of a tape and for advancing the tape, a conveyor for moving matrices after composition to redistribute

75

them into said channels, a clutch for communicating power to said tape sensing and advancing mechanism, means including a normally deenergized electromagnet, circuit connections under the control of said conveyor for energizing said electromagnet to disengage the elements of said clutch and arrest said mechanism, and a device supervised by said conveyor for controlling said circuit connections comprising a pair of weighted arms pivotally supported in a longitudinal position parallel to said conveyor, a coil spring for urging said weighted arms inwardly, and a contact actuator moved by said coil spring in one direction and by said weighted arms in another direction when said device is rotated by said conveyor to control said circuit connections.

3. In a linecasting and composing machine, a storage magazine having a plurality of channels each adapted to receive a class of slug casting

matrices, a plurality of release elements each associated with one of said channels for releasing said matrices under the supervision of a control form, a mechanism for sensing and advancing said control form, a conveyor for moving matrices after the composition of each line to redistribute them into said channels, a clutch having elements for communicating power to said tape sensing and advancing mechanism, means under the control of said conveyor to disengage the elements of said clutch comprising a rotatable shaft, a pair of weighted arms supported on said shaft for centrifugal action, a coil spring in axial alignment with said shaft for urging said weighted arms in opposition to their centrifugal tendency, and a contact closing member moved in one direction by said coil spring and in an opposite direction under the control of said weighted arms.

MAURUS T. GOETZ.
